UNITED STATES PATENT OFFICE.

CARL ALBERT HELLDÖV AND GEORG AXEL GABRIEL LÖFSTRÖM, OF Malmö, SWEDEN.

WATER TAP.

Application filed January 31, 1924. Serial No. 689,664.

To all whom it may concern:

Be it known that we, CARL ALBERT HELLDÖV and GEORG AXEL GABRIEL LÖFSTRÖM, both citizens of Sweden, and residing at Malmo, Sweden, have invented a certain new and useful Water Tap, of which the following is a specification.

As is well known the tightening washer in the usual water tap is worn considerably by the daily use of the tap, and therefore the washer requires to be renewed after a relatively short time. In order to replace this washer without turning off the water at the main tap, it has been proposed to provide in addition to the usual valve for opening and closing the tap a secondary valve acting in the opposite way to the former and arranged on the opposite side of the seating for the former valve, said secondary valve automatically closing the through-passage in the tap, when the first-named valve is removed a certain distance from its seating. The devices hitherto proposed do not however solve the problem in a satisfactory manner, and for instance in one of the proposed constructions the drawbacks arise that the valve spindle is acted upon by the water pressure in such disadvantageous manner that the spindle is subjected to great strains. In another heretofore proposed construction the water supply is cut off much too suddenly, so that the water pipes are subjected to such great strains that the adaptation of this device is connected with the risk of damaging the water pipes. Moreover this last named construction is much too complicated and expensive. In still another proposed construction the second tightening member consists of a ball or the like, whereby the disadvantages arise that the ball vibrates in the piping, thereby producing troublesome noise, and that the usual tightening member including the hand wheel must be substituted by a screw sleeve which does not secure effective tightening.

The present invention has for its object to eliminate these drawbacks attached to the older constructions. For this purpose the usual closing device comprising the spindle and the hand wheel has been retained, the secondary valve is well guided and is acted upon by the water pressure in exactly axial direction, so that it cannot become jammed, and the usual tightening valve can be retained in its usual form but

it can of course be made to close the tap opening automatically in a known manner without departing from the invention.

In the accompanying drawing the invention has by way of an example been illustrated as applied to a horizontal type of water tap;

Figure 1 being a vertical section and

Figures 2 and 3 being views of the secondary valve seen from one end and one side respectively.

Referring to the drawing 1 is the water tap body, 2 the outlet, 3 the ordinary main valve, 4 the screw spindle of the latter and 5 the secondary valve. According to the invention the main valve 3 and the secondary valve 5 are arranged to tighten on seatings formed by the extreme annular end surfaces of a cylindrical part 7 of the water tap body 1, said cylindrical part serving as a guide for the wings 6 arranged on the secondary valve 5. This arrangement ensures that the secondary valve 5 is disposed immediately behind the main valve 3 so that it requires the least possible space and at the same time is provided with the best possible guiding means. The secondary valve is inserted in its place through the connecting piece 8 arranged in line with the cylindrical part 7. A stop ring 9 or the like may after insertion of the secondary valve be screwed in into the connecting piece 8 so as to prevent the secondary valve from falling out. As will be seen from the drawing, substantially the usual form of water tap can be retained in spite of the addition of the secondary valve, and the price of the improved water tap will not be augmented essentially. The construction is extraordinarily simple, as one extra part only has been added, namely the secondary valve which in itself is of the simplest and therefore most reliable construction. The secondary valve is acted upon by the water pressure in exactly axial direction so that it cannot become jammed. The secondary valve normally abuts against the closed main valve 3 and will automatically be closed when the main valve is sufficiently withdrawn from its seating. It is however to be observed that this action per se is not new, but that the novelty of the invention is based upon the formation of the water tap body with a cylindrical guide for guiding the secondary valve, said valve being provided with guiding wings and arranged immediately behind the seating for

- the ordinary valve. The seatings for the main valve and the secondary valve have also previously already been arranged at the extreme ends of a short cylindrical through-
5 passage or bore in the water tap body, but with such an arrangement, which presupposes a guide of another nature for the secondary valve and also a modified construction of the tap body, the same simple ar-
10 rangement of the secondary valve as disclosed by the present invention is not intended or obtained; and according to the present invention the indicated cylindrical part of the tap body is adapted to form the guide for the secondary valve and obviously there-
15 fore must have a length and a diameter in correspondence with the said purpose, which conditions are lacking in the older construc-
tions.
- 20 What we claim and desire to secure by Letters Patent is:—
- In a water tap, the combination of a body or casing provided at one end with an internally-threaded connecting portion constituting a water inlet, and at its other end with a hollow plug having an internally-threaded part; a laterally-projecting discharge spout adjacent the plug; said body also comprising a cylindrical, central portion which forms an integral part thereof and the extreme opposite end surfaces of which constitute annular valve seats disposed interiorly of the body; the connecting
- 30

portion of said body, the two valve seats and the bore of the plug being disposed in co-
35 axial relation; a main valve to engage the front valve seat; an operating spindle ex-
tending through said plug bore and connected to said valve and having an exter-
nally-threaded part engaged with the inter-
40 nationally-threaded part of the plug; a secondary valve adapted to be inserted through the connecting portion of the tap body into po-
sition to engage the rear valve seat and hav-
ing forwardly-extending, radially-arranged 45 guide wings of greater length than the cy-
lindrical portion of said body which project into and through that portion and abut against the main valve at their free ends, whereby the secondary valve will be spaced 50 from its seat by the main valve when the latter is closed, but will be moved against its seat by the pressure of the in-coming water as the main valve is moved away from the respective seat by the operation of said spin-
55 dle; and a stop ring threaded into said connecting portion to prevent loss of the sec-
ondary valve.

In testimony whereof, we have signed our names to this specification in the presence of 60 two subscribing witnesses.
